UNITED STATES PATENT OFFICE.

ROBERT G. FLEMING, OF BLOOMFIELD, NEW JERSEY, ASSIGNOR TO SMOKADOR MANUFACTURING CO., INC., OF NEW YORK, N. Y., A CORPORATION OF DELAWARE.

DESIGN FOR A SMOKER'S ASH STAND.

Application filed March 23, 1925. Serial No. 12,824. Term of patent 14 years.

To all whom it may concern:

Be it known that I, ROBERT G. FLEMING, a citizen of the United States, residing at Bloomfield, county of Essex, State of New Jersey, have invented a new, original, and ornamental Design for a Smoker's Ash Stand, of which the following is a specification, reference being had to the accompanying drawing, forming a part thereof.

Fig. 2 is a top plan view, and
Fig. 3 is a bottom plan view of the smoker's ash stand, showing my new design.

I claim:

The ornamental design for a smoker's ash stand, as shown.

R. G. FLEMING.
